(57) **CLAIM**

The ornamental design for a formed door for a refrigerator, as shown and described.

DESCRIPTION

FIG. 1 is a front perspective view of the design of the formed door for a refrigerator;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines shown are for illustrative purposes only and form no part of the design claimed.
